CLAIM

The ornamental design for a clip-on sunglasses, as shown and described.

DESCRIPTION

FIG. 1 is a front elevational view of clip-on sunglasses showing our new design;

FIG. 2 is a rear elevational view thereof;

FIG. 3 is a top plan view thereof;

FIG. 4 is a bottom plan view thereof;

FIG. 5 is a right side elevational view thereof, the left side elevational view being a mirror image;

FIG. 6 is a right side elevational view thereof in the alternate position of the sunglass portion turned away from the clip portion, the left side elevational view being a mirror image;

FIG. 7 is a perspective view of a modified embodiment of the design shown in FIGS. 1-6, wherein the nose piece and clips are shown gray and the post extending from the nose piece to the clips is red;

FIG. 8 is a perspective view of a second modified embodiment of the design shown in FIGS. 1-6, wherein the nose piece and clips are shown gray and the post extending from the nose piece to the clips is blue; and,

FIG. 9 is a perspective view of a third modified embodiment of the design shown in FIGS. 1-6, wherein the nose piece and clips are shown gray and the post extending from the nose piece to the clips is orange.
